ROLL PACKAGE

Edward J. Heizer, West Caldwell, N. J., assignor
to Congoleum-Nairn Inc., a corporation of New
York

Application September 1, 1938, Serial No. 227,895

4 Claims.

(Cl. 206—59)

This invention relates to means for packaging rolled sheet material, especially rolled sheet material of a heavy and bulky character such as rolls of linoleum and felt base yard goods.

Rolls of linoleum and felt base yard goods are usually shipped by the manufacturer in rolls which may be about 8, 12 or 16 feet in length. Rolls may weigh about 500 or 600 pounds. Linoleum rolls are usually wrapped in paper and the wrapped roll is placed in a suitable crate. Small rolls of felt base yard goods are sometimes shipped using no crate at all. For larger rolls, however, the felt base yard goods is usually put up in crates for the purpose of shipment.

The crates which have usually been used heretofore consist of end pieces at each end of the roll, the end pieces being connected together by slats extending longitudinally of the roll along the outside thereof. The slats are used only on opposite sides of the roll and are tied across by cross pieces or battens. When the rolled sheet material is packed in a crate of this character (and when no crate at all is used) the ends of the rolls are frequently injured during the handling of the crates in which the rolls are contained. In shipping, handling and transferring the heavy rolls, the goods are frequently dropped in such fashion that the end edge of the roll receives a heavy blow; and as a result of such blows the edges of the material, which are somewhat friable, are often substantially damaged.

It is an object of this invention to provide a package for rolled sheet material such as rolled linoleum and felt base yard goods which minimizes injury to the ends of rolls due to careless handling of the rolls during shipment.

It is a feature of this invention that there is placed at at least one end of the package a cushion plate or support plate such as a board, the structure of which will be described more in detail hereinbelow. The cushion plate or support plate is positioned in the package in a way which minimizes the injurious effects of shocks received at the end edges of the package. This is accomplished by the use of a structure that causes impact shocks to be centered more nearly at the center of the roll of rolled sheet material than is the case when an ordinary crate is used. The use of a structure adapted to center the shock is preferably combined with the use of parts having sufficient resiliency to offer a cushioning effect at the end of the package.

The cushion plate or support plate, when combined with the end piece at one end of the

package constitutes as a whole a shock absorbing means. From a general point of view the shock absorbing means is characterized primarily by the fact that it includes a marginal recess which extends inwardly from the margin and which is between the surface of the supporting plate abutting the end of the roll of rolled sheet material and the outer surface of the end piece. By this construction the shock received at the margin of the end piece is transmitted to the support plate at a point which is no nearer the margin of the support plate than the distance by which the bottom of the recess is spaced from the margin of the support plate. The shock is, therefore, concentrated centrally away from the plies of the rolled sheet material at the outer edge of the roll so that it is received by the bottom of the rolled sheet material as over a whole of its radial thickness rather than being concentrated at a small area adjacent the outer edge of the rolled sheet material. Moreover, since the end piece and the support plate have some resiliency even though made of relatively heavy pieces of wood, the slight marginal yielding of these parts serves to reduce the severity of any shocks to which the plies of the rolled sheet material at the margin of the roll may be subjected.

Further purposes, features and advantages of this invention will be apparent in connection with the following description of certain illustrative embodiments of this invention, the description being in connection with the accompanying drawing wherein—

Fig. 1 is a side elevation partly in section of a crate which embodies this invention and which contains rolled sheet material;

Fig. 2 is a sectional view of the crate shown in Fig. 1 taken on the line 2—2 of Fig. 1;

Fig. 3 is a perspective view of the support plate which is used in the device shown in Figs. 1 and 2;

Fig. 4 is a perspective view of a modified form of support plate which may be used in connection with the crate shown in Fig. 1;

Fig. 5 is a side elevational detail view partly in section of an alternate form of shock absorbing means embodying this invention;

Fig. 6 is a side elevational detail view of another alternate type of package embodying this invention, the package in this case being made up without slats or battens externally disposed with respect to the rolled sheet material;

Fig. 7 is a side elevational detail view of a modification of the package shown in Fig. 6;

Fig. 3 is a side elevational view partly in section of the shock absorbing means at the end of the package shown in Fig. 6.

Referring to Figs. 1, 2 and 3 of the drawing, the package is in the form of a crate comprising end pieces indicated generally by the reference character 10 and which may be made of a single part or of a plurality of parts. The end piece of the embodiment shown in the drawing consists of parallel boards 10' and cross boards 10² secured together by nails 10³, this type of structure affording ample strength for carrying large rolls of linoleum, for example. The end piece can be made up in any other suitable way depending on the size of the package and the weight of the goods to be carried thereon. Slats 11 are secured to opposite margins of each of the end pieces 10 by any suitable means such as nails 12. The cross pieces or battens 13 are secured to the end pieces and/or the slats 11 by any suitable means such as nails 14.

Within the crate is a roll 15 of sheet material which, as aforesaid, may be linoleum or felt base yard goods. The roll of material may be wound around a hollow core member 16, as is common practice in the shipment of goods of this character and may be covered with a paper wrapping (not shown).

At one end of the crate is the support plate indicated generally by the reference character 17. In this embodiment of my invention, the support plate is square and is of sufficient area on the upper surface thereof to support all of the plies of the rolled sheet material at one end of the roll when the package is placed on end. The opposite side of the support plate 17 includes chamfered parts 18, leaving a bottom surface 19 which is adapted to abut against the end piece 10. In the embodiment shown the support plate is about $\frac{1}{8}$ inch thick and may range from about 10 inches to 13 inches square. Each chamfered part is about 2 inches wide and is at such an angle that the plate is decreased in thickness by a maximum of about $\frac{1}{8}$ inch at each margin.

As is clearly apparent from Fig. 1, the chamfered parts 18 afford a recess between the surface of the support plate adjacent the plies of rolled sheet material and the outer surface of the end piece. In Fig. 1 the action of the support plate is illustrated when the crate is dropped on a side edge of the crate. It may be noted that the shock that is received at the corner of the crate is transmitted to the support plate so as to be centered a substantial distance inwardly from the margin of the support plate. This is indicated by the arrows in Fig. 1. The end piece 10 which protrudes outwardly from the base of the recess being of some material such as wood, has at least some resiliency. Also, the portion of the support plate overlying the recess possesses some resiliency, preferably being made of a material such as wood. Due to the shifting of the location of the strain imposed by a blow from the edge of the support plate toward the center of the support plate, the likelihood of injury resulting from blows and shocks of the character above mentioned is greatly reduced. The protection against injury from blows of this character is increased to some extent by having the end piece or support plate, or both, made of a resiliency material and by having the parts thereof overlying the recess of such dimensions that the resiliency of the material is taken advantage of to reduce the harmful effects of shocks received at the end edges of the crate.

As above mentioned, crates are usually constructed with large slats on two opposite sides thereof and have cross battens on the other two sides. In handling a crate of this character, it is almost always moved from a horizontal position to a vertical position with one side having the long slats downward. For this reason, it is not essential to chamfer all four margins of the support plate. The support plate may be made with only two opposite marginal portions thereof chamfered, as shown in Fig. 3, and in such case the chamfered portions of the support plate are placed in proximity to the long slats of the crate. The chamfered portions 18 are preferably cut across the grain rather than in a direction with the grain so as to minimize the danger of splitting the support plate.

If desired, a modified form of support plate may be used such as the support plate shown in Fig. 4, the support plate in this figure being indicated generally by the reference character 20. The support plate includes the chamfered portions 21 which in this case are along each margin of the support plate. In order to guard against splitting of the support plate, a piece of ply wood 22 may be adherently united to the upper surface of the support plate with the grain thereof set at an angle to the grain of the body portion 23 of the support plate. This form of support plate is used advantageously in a carton, crate or similar container which is closed on all four sides.

The shock absorbing means may be placed at either or both ends of the package, as may be desired. For practical purposes it is only necessary, however, to place the shock absorbing means at one end of the package, inasmuch as the package may be marked so as to clearly point out the end of the package on which the package is to stand.

In Fig. 5 an alternate form of shock absorbing means is shown. This form is shown to illustrate the fact that it is not always essential to use a chamfered piece as part of the shock absorbing means. The crate shown in Fig. 5 may be similar to that shown in Fig. 1 and may comprise the slats 24, the battens 25 and suitable end pieces (the end piece at one end only being shown and indicated generally by the reference character 26 and being composed of two boards 26', held in place by the slats and battens, e. g. by nails 26²). In this modification the support plate 27 is in the form of a square piece of wood. The support plate 27 is spaced from the end piece 26 by an intervening board 28 which has a substantially less width in at least one dimension than either the total width of the end piece or the total width of the support plate 27. The board 28 may be attached either to the end piece 26 or to the support plate 27 by any suitable means (not shown) so as to maintain the board in proper position relative to the other parts of the shock absorbing means at the end of the crate. In the first case the board 28 may be regarded as part of the end piece, and in the second case may be regarded as part of the support plate, it being apparent that the end piece or the support plate or both may, as shown in Figs. 1 and 4 as well as Fig. 5, be made of one piece or of a plurality of pieces. In this construction it will be noted that the board 28 serves to space the marginal portion of the support plate 27 from the marginal portion of the end piece 26 by a recess extending inwardly from the marginal portion of the shock absorbing means between the upper surface of the support plate and the outer surface of the

end piece. This recess serves the purposes which have been referred to more in detail hereinabove in connection with the form of device embodying this invention that includes a chamfered support plate.

In Figs. 6 and 8 a modified form of package is shown. In this case slats or other crating means disposed externally along the sides of the rolled sheet material are dispensed with. In this form of package the ends only of the roll of rolled material are protected against injury. For this purpose an end piece 30 is used in conjunction with a support plate 31. The end piece and support plate are of disk shape and preferably are attached to each other by suitable means such as an adhesive. The margin of the support plate is chamfered at 32 so as to provide a recess between the margin of the support plate and the margin of the end piece.

In order to maintain the shock absorbing means in position, any suitable device may be used. In the form shown an elongated bolt or rod 33 is used that is adapted to extend through a hollow core at the interior of the roll 15 of rolled sheet material from the shock absorbing means at one end of the roll to an end piece (not shown) at the opposite end of the roll. The bolt may, as shown, pass through an opening 34 in the shock absorbing means, the nut 35 at the end of the bolt being placed in a suitable recess 36 so as not to protrude from the end of the shock absorbing means. In order to keep the shock absorbing means properly centered, a tapered plug 37 is preferably used that is adapted to fit within the core 16 (see Fig. 1). The plug may be secured to the shock absorbing means by any suitable means such as nails 38.

When the type of shock absorbing means shown in Figs. 6 and 8 is used, the rolled sheet material is preferably first wrapped in paper to protect the outer wall thereof. The shock absorbing assembly may then be placed at either or both ends of the rolled sheet material and secured in place by the bolt 33.

In order to make the construction more rugged and in order to prevent splitting, the end piece 30 is preferably made of ply wood. When the support plate is about 10 to 13 inches in diameter the end piece is preferably about $\frac{1}{2}$ inch less in diameter than the diameter of the support plate and is about $\frac{1}{4}$ inch in thickness. The support plate as shown is about $\frac{5}{8}$ to $\frac{7}{8}$ inch in thickness and the chamfer along the margin thereof is about $1\frac{1}{8}$ inches in width and is cut at such an angle that the thickness of the plate is reduced by about $\frac{1}{2}$ inch at the outer edge. Moreover, the support plate 32 preferably has a piece of ply wood 39 adherently united to the upper face thereof.

In Fig. 7 a modified form of this invention is shown. In this case the end piece 40 is chamfered rather than the support plate. The support plate is in the form of a disk 41 of uniform thickness. The end piece and support plate may be held together and maintained in proper position at the end of the rolled sheet material in the manner described above in connection with Figs. 6 and 8.

From the foregoing description, it is apparent that structures embodying this invention may take many different forms. The recess between the bottom of the end piece and the upper surface of the support plate may be made in a variety of different ways. The use of two pieces and chamfering one of them is to be preferred, al-

though any other method of undercutting one or the other, or both, of these parts may be employed to secure a similar result. Moreover, the recess may be produced without cutting away any member of the shock absorbing means, as illustrated in connection with Fig. 5, wherein the parts are selected and assembled so as to bring about a result which is comparable with that which may be obtained by chamfering or undercutting either the end piece or support plate. The recess is preferably such that the base of the recess is disposed inwardly from the margin of the support plate (or end piece) by a distance which is about 35% of the distance from the margin of the support plate (or base plate) to the center thereof. While these proportions for the parts of the shock absorbing means is preferable, the proportions may be varied widely. In order, however, to achieve the advantages of this invention to a commercially desirable extent the base of the recess should be disposed so as to be at least about 20% of the distance inwardly from the margin of the support plate (or base plate) to the center thereof. Since the rolled sheet material is usually of about the same outside diameter as the support plate, the proportions named apply to the rolled sheet material, as well as to the support plate therefor as to the extent to which the rolled sheet material should be undercut by the recess in the shock absorbing means. It is to be understood that the structures which have been shown and described hereinabove have been referred to merely for the purpose of affording illustrative examples of the practice of this invention and that the scope of this invention is to be limited only by the language of the appended claims.

I claim:

1. Packaged rolled sheet material comprising a roll of sheet material, a support plate at one end of said roll the inner face of which is arranged to support the entire surface presented by the edges of the rolled sheet material at said end, and an end piece underlying and in plane contact with said support plate, the margin of said support plate being spaced from said end piece at least along opposite portions of said support plate by a recess extending inwardly a substantial distance beneath the plies of said rolled sheet material so that shocks to a marginal portion of said end piece are received by a portion of said support plate underlying those plies of rolled sheet material which are spaced inwardly from the outermost plies of said rolled sheet material supported by said support plate, the area of contact between said end piece and said support plate being equal to at least approximately one-half the area of the support plate in contact with said plies whereby rocking movement between said support plate and said end piece is effectively prevented.

2. Packaged rolled sheet material comprising a roll of sheet material, end pieces at opposite ends of said package, slats extending between marginal portions of said end pieces and attached thereto to maintain said end pieces connected together, a support plate at one end of said roll the inner face of which is arranged to support the entire surface presented by the edges of the plies of the rolled sheet material at said end, and which has a substantial portion of the opposite face in plane contact with one of said end pieces, the margin of said support plate being spaced from said adjacent end piece at least along opposite portions of said support plate by

a recess extending inwardly a substantial distance beneath the plies of said rolled sheet material so that shocks to a marginal portion of said end piece are received by a portion of said support plate underlying those plies of rolled sheet material which are spaced inwardly from the outermost plies of said rolled sheet material supported by said support plate, the area of contact between said end piece and said support plate being equal to at least approximately one-half the area of the support plate in contact with said plies whereby rocking movement between said support plate and said end piece is effectively prevented.

3. Packaged rolled sheet material comprising a roll of sheet material and a shock absorbing means at at least one end thereof, said shock absorbing means comprising a disc-shaped support plate the inner face of which is arranged to support the entire surface presented by the edges of the plies of the rolled sheet material at said end, a disc-shaped end piece in plane contact with said disc-shaped support plate and on which end piece said package is adapted to rest when standing on an end thereof, and an inwardly extending annular recess between the marginal portion of said support plate and the marginal portion of said end piece, said recess extending inwardly a substantial distance beneath the plies of said rolled sheet material so that shocks to a marginal portion of said end piece are received by a portion of said support plate underlying those plies of rolled sheet material which are spaced inwardly from the outermost plies of said rolled sheet material supported by said support plate, the area of contact between said end piece and said support plate being equal to at least

approximately one-half the area of the support plate in contact with said plies whereby rocking movement between said support plate and said end piece is effectively prevented.

4. Packaged rolled sheet material comprising a roll of sheet material and a shock absorbing means at opposite ends thereof, each shock absorbing means comprising a disc-shaped support plate the inner face of which is arranged to support the entire surface presented by the edges of the plies of the rolled sheet material at an end thereof, a disc-shaped end piece in plane contact with each disc-shaped support plate on which end piece said package is adapted to rest when standing on one end thereof, and an inwardly extending annular recess between the marginal portion of each support plate and the marginal portion of the adjacent end piece, said recess extending inwardly a substantial distance beneath the plies of said rolled sheet material so that shocks to a marginal portion of said end piece are received by a portion of said support plate underlying those plies of rolled sheet material which are spaced inwardly from the outermost plies of said rolled sheet material supported by said support plate, the area of contact between said end piece and said support plate being equal to at least approximately one-half the area of the support plate in contact with said plies whereby rocking movement between said support plate and said end piece is effectively prevented, and means including a rod extending through a core at the interior of said roll of sheet material for maintaining said shock absorbing means and said roll of sheet material in unitary relation.

EDWARD J. HEIZER.
